M. O. JENSEN,
SPRING CLAMP,
APPLICATION FILED JAN. 17, 1921.

1,409,551.

Patented Mar. 14, 1922.

UNITED STATES PATENT OFFICE.

MILTON O. JENSEN, OF CHICAGO, ILLINOIS, ASSIGNOR OF ONE-HALF TO RICHARD FUCHS, OF CHICAGO, ILLINOIS.

SPRING CLAMP.

1,409,551.

Specification of Letters Patent. Patented Mar. 14, 1922.

Application filed January 17, 1921. Serial No. 437,919.

To all whom it may concern:

Be it known that I, MILTON O. JENSEN, a citizen of the United States, residing at Chicago, in the county of Cook and State of Illinois, have invented certain new and useful Improvements in Spring Clamps; and I do declare the following to be a full, clear, and exact description of the invention, such as will enable others skilled in the art to 10 which it appertains to make and use the same.

This invention relates to an improved spring clamp for use in connection with a spring of the elliptical or semi-elliptical 15 type formed of superposed strips of spring metal, the clamp being used when one or more of the strips which form the spring break. One object of the invention is to so construct 20 this clamp that it may be put in place and hold the spring strips tightly in engagement, the clamp holding the broken strip or strips against longitudinal and transverse movement and tightly clamping the strips together so that the broken strip or strips will 25 be held in tight binding engagement with the unbroken strip or strips and the broken strip parts held in contact with each other, the unit spring retaining its original form and size.

30 Another object of the invention is to provide an improved construction of compressor carrying cross bar and improved means to releasably hold the cross bar in an operative position.

35 Another object of the invention is to so construct the U-shaped clamp body and compressor carrying cross bar that the cross bar may be swung pivotally upon one arm and brought into engagement with the sec- 40 ond arm and then moved longitudinally upon the arms and held against pivotal movement to a releasing or inoperative position.

Another object of the invention is to so 45 construct the U-shaped body portion of this clamp that it will be prevented from having turning movement upon the spring when put in place and the compressing means tightened.

50 Another object of the invention is to so construct the clamp that the pivotally mounted cross bar will be prevented from interfering with placing of the clamp about the broken spring.

55 Another object of the invention is to so construct the clamp that it may be easily

and quickly assembled and securely held in the assembled position, each of the arms of the U-shaped body portion having a head at its end and one of the heads being formed 60 separate from the arms and securely held in place after the cross bar has been placed upon the arm for sliding and pivotal movement thereon.

This invention is illustrated in the accompanying drawings, wherein:

65 Figure 1 is a view showing the improved clamp in vertical section and applied to a spring having one of the resilient strips broken.

Figure 2 is a view showing the clamp in 70 end elevation and looking in the direction of the arrow A in Fig. 3.

Figure 3 is a view showing the clamp in side elevation, the compressing means and the cross bar carrying the same being partially shown in section.

Figure 4 is a view taken along the line 4—4 of Fig. 3.

Figure 5 is a sectional view taken along the line 5—5 of Fig. 3.

80 This improved clamp is for use in connection with an elliptical or semi-elliptical spring, a portion of which is shown in Fig. 1 and indicated in general by the numeral 1. This spring is of a conventional construction 85 and is formed of a plurality of resilient strips 2, one of which is shown broken. If a spring strip breaks, it is liable to work longitudinally or transversely out of place and it is the object of this spring clamp to prevent the broken strip from working loose 90 and also serve to tightly clamp the strip together at the break so that the spring will not be weakened.

95 This clamp is provided with a U-shaped body 3 having a cross head 4 and side arms 5 and 6, the cross head and the upper end portions of the side arms 5 and 6 being provided with integral side strips 7 which serve to provide wide bearing faces for engaging the spring and preventing the clamp from turning upon the spring when the spring compressing means is tightened as will be 100 hereinafter brought out. Below the side strips 7 of the arms, these arms are offset as shown clearly in Fig. 3 and below these side strips 7, the offset portions of the two arms will be circular in cross section as shown thus permitting the cross bar 8 to be slidably and 105 pivotally mounted upon the lower portion of 110

the arm 6. The free end portion of this arm 6 is somewhat reduced and threaded as shown at 9 in Fig. 4 and carries a nut 10 which is put in place after the cross bar has been placed upon the arm. This nut 10 which is to form a head for the arm 6 has its threaded opening which receives the threaded end portion 9 of the arm enlarged at its outer or lower end as clearly shown in Fig. 4 so that after the nut has been put in place, the end portion of the arm may be formed into a rivet head thus preventing removal of the securing nut. The arm 5 is provided with a head 11 having a rounded end and in the preferred form, the outer end of the nut 10 and the end of the arm 6 which is formed into the rivet head will be rounded so that the arms will each be provided with a head having a rounded end. It will thus be seen that the two heads will be of a similar appearance when the nut or head 10 is put in place.

The cross bar 8 which is pivotally and slidably mounted upon the arm 6 of the body is provided with an enlarged central portion having a threaded opening formed therein and thus providing a threaded bearing 12 through which passes the threaded stem 13 of the compressor. This stem is provided with a turning head 14 at its outer or lower end and with a work engaging head 15 at its upper end which is in swivel connection with the stem as shown at 16 so that the stem may be rotated to compress the spring 35 without the head 15 turning with the stem. A clamping nut 17 is provided upon this stem for engaging the underface of the bearing 12 and securely locking the stem against rotary movement after the spring 40 has been tightly compressed. The free end portion of this cross bar is provided with a circular opening 18 having a side entrance 19 which is of less diameter than the diameter of the opening 18. The arm 5 of the 45 U-shaped body has its side portions cut away as shown in Fig. 3 and in Fig. 5 thus providing a reduced neck 20 which is of proper diameter for passing through the entrance 19. It will thus be seen that when the cross 50 bar is swung upon the arm 6, the reduced neck may pass through the entrance 19 into the opening 18 and the cross bar may then be moved along the arms 5 and 6 towards the heads 10 and 11 so that the portion of the 55 arm 5 between the neck 20 and the head 11 will be positioned in the opening 18. This opening 18 is of the proper size to receive the arm 5 and permit free sliding movement of the cross bar upon the arm but the entrance 19 is too small to permit the arm 5 to 60 pass out through the entrance when the cross bar is in the operative position shown in Figs. 2, 3 and 4. Therefore, there will be no danger of the cross bar turning upon the 65 arm 6 and slipping out of the operative posi-

tion when in use as it is necessary to move the cross bar upwardly to pass the reduced neck 20 through the passage 19 before the cross bar can be swung out of the operative position.

When this device is in use, the cross bar will be swung outwardly so that its free end extends away from the arm 5 instead of towards the same. The clamp will be put in place upon the spring and will fit snugly 75 within the portion of the U-shaped body provided with the side strips. By having the end portions of the arms offset as shown in Fig. 3, the heads 10 and 11 will not interfere with the placing of the clamp upon the 80 broken spring.

After the clamp is in place, the cross bar will be moved away from the head 10 of the arm 6 and then swung to the operative position with the neck 20 passing through the 85 entrance 19 and into the opening 18. The cross bar will then be allowed to drop down upon the two heads 10 and 11 and the compressing screw 13 will be turned by means of a suitable wrench engaging the turning 90 head 14. This will bring the swivel head 15 into engagement with the underface of the spring and continue turning of the screw or threaded stem will tightly compress the spring and securely hold the broken spring 95 in place. After the stem has been tightened as much as desired, the securing nut 17 will be tightened and the stem will be securely held in place. When a permanent repair is to be made to the spring, the nut 17 will be 100 loosened and the stem can then be turned and moved out of engagement with the spring after which the cross bar can be moved upwardly upon the arms and then swung to the inoperative position thus permitting removal of the clamp. It will thus be seen that there has been provided a clamp so constructed that it can be easily and quickly put in place and so constructed that there will be no danger of the cross bar accidentally slipping out of the operative position. It will be further noted that provision of the side strips 7 will tend to prevent turning of the U-shaped body upon the spring when the threaded stem is tightened, 115 and therefore, the clamp will be held in the proper position when in use.

What is claimed is:

1. A clamp comprising a U-shaped body having a cross head and side arms, the cross head and upper portions of the side arms being provided with side extensions to provide relatively wide bearing faces, and compressing means carried by the side arms, the free end portions of the arms below the 120 side extensions being circular in cross section and the compressing means being pivotally and slidably mounted upon the free end portion of one arm and having its second end portion cut from one side whereby the 125

compressing means may be swung into position for slidably and releasably engaging the second arm.

2. A clamp comprising a work engaging body having side arms having their end portions circular in cross section and terminating in heads, one arm adjacent its head having its side portions cut away to provide a reduced and flattened neck, a cross bar pivotally and slidably mounted upon the second arm and having in its free end portion an opening for slidably receiving the first arm, the opening having a reduced side entrance for receiving the reduced neck when moving the cross bar on and off of the first arm and compressing means carried by the cross bar.

3. A clamp comprising a body having side arms, each having a head at its free end and one having a reduced neck adjacent to but spaced from its head, and a compressor carrying cross bar pivotally and slidably mounted upon the second arm and having its free end portion provided with an opening having a reduced side passage for receiving the neck of the first arm when the cross bar is swung into engagement with the first arm, the cross bar being then moved

along the arms to engage the heads thereof with the portion of the first arm between the neck and head thereof positioned in the opening at the free end of the cross bar and preventing swinging of the cross bar to an inoperative position.

4. A clamp comprising a body having side arms, each having a head at its free end and one having a reduced neck adjacent to but spaced from its head, and a compressor carrying cross bar pivotally and slidably mounted upon the second arm for movement into and out of engagement with the first arm, the cross bar when having engagement with the first arm at the neck thereof being slidably and pivotally mounted and when in engagement with the portion of the first arm between the neck and head thereof being held against pivotal movement.

5. The structure of claim 1 having the compressing means pivotally and slidably engaging one arm and slidably and releasably engaging the second arm and held against pivotal movement when moved towards one end of the second arm.

In testimony whereof I have hereunto set my hand.

MILTON O. JENSEN.
